UNITED STATES PATENT OFFICE

2,083,265

AUTOGRAPHIC REGISTER

Louis Jensen, Chicago, Ill., assignor to United Autographic Register Co., Chicago, Ill., a corporation of Illinois

Application December 3, 1934, Serial No. 755,815

4 Claims. (Cl. 282—16)

This invention relates to autographic registers and more particularly to improved mechanism for advancing the stationery and insuring proper refolding of a record strip in the record compartment of the machine.

The primary object of the invention is to provide a compact stationery-feeding unit which may be used in various register casings handling forms of different widths.

A further object of the invention is to provide a mechanism for refolding and compressing stationery in the same zigzag folds that were made in the supply compartment of the machine. In order to accomplish this a special indicating device has been provided external of the register casing to indicate the position of the guiding mechanism with respect to the feeding mechanism.

The invention is illustrated in a preferred embodiment in the accompanying drawings, in which—

Fig. 1 is a broken longitudinal sectional view of an autographic register embodying the invention, taken as indicated at line 1 of Fig. 5; Fig. 2 is a broken plan view of the same showing the platen and indicating device; Fig. 3 is a broken sectional view taken as indicated at line 3 of Fig. 5; Fig. 4 is a sectional view taken as indicated at line 4 of Fig. 5; Fig. 5 is a transverse vertical sectional view of the feed and presser mechanism; and Fig. 6 is an elevational view of the indicating member.

In the embodiment illustrated, A designates a casing having a skeleton cover A'; B, a stationery-feeding unit; C, presser-mechanism actuated by the feeding mechanism; and D, guiding means within the record compartment of the register actuated by the feeding mechanism.

The register A may be of the usual sheet-metal construction and is shown provided with a depressed bottom member 10 to afford more clearance in the supply compartment 11 and the record compartment 11a. A transverse guide roller 12 is journaled in the front of the supply compartment which is accessible through a door 13 hinged to the casing at 14 and is provided with an angular guide member 15 which cooperates with the guide roll in preventing the stationery strips 16 from improperly leaving the supply compartment. The crank side of the supply compartment is provided with a carbon-roll chamber 17 which is provided with a cover-member 18 pivotally connected to the machine at 19. Carbon strips 20 may be drawn from the compartment 17 across the platen 21 in interleaved

relation with the stationery strips 16 in the well-known manner. The record-compartment 11a is also provided with a door 22 to enable the record copies to be removed from the machine as desired.

The skeleton cover A' is pivotally connected near the center of the casing and provides a housing 23 for a presser-roll 24 and shaft 25. The transverse jack shaft 25 is urged downwardly by means of springs 26 bearing against journal members 27, and the right end of the shaft, as viewed in Fig. 5, is equipped with a gear 28 to insure rotation of the presser-roll 24 with the same peripheral speed as the feed-roll described below. The cover is provided at its rear end with a tear-off edge 29 on which the issuing strips may be severed in the usual manner.

The stationery feeding unit B comprises a U-shaped unitary frame member having a front wall 30 and side walls 31. The lower portion 32 of the front wall is turned forwardly and forms a flange by which the unit is removably connected to the floor 10 of the machine. The upper end of the front wall is turned rearwardly to form the slotted top wall 33 of the unit and has downwardly extending arms 34 which are rigidly connected to the side walls 31 and provide a very rigid construction. A feed roll shaft 35 is journaled in the side walls of the frame and has one end extending outwardly through the casing A to connect with the operating crank 36. As shown in Figs. 2 and 5, the casing is provided with a depressible button 36a to limit the crank to one complete revolution at a time. A mutilated feed wheel 37 provided with a cam 38 is rigidly connected to the shaft 35. The wheel is provided with segments 37a secured in position by means of screws 39 so that the wheel may be adjusted to accommodate various lengths of forms. The shaft is further provided with a cam 40 to operate the presser-mechanism C described below. A U-shaped supporting plate 41 is pivotally mounted on a shaft 42 journaled in the side walls 31 of the frame. A coil spring 43 encircles the shaft and urges the plate forwardly. The plate has two upwardly extending arms whose edge portions 44 are turned rearwardly to provide journals for pivots 45 upon which jogging fingers 46 are mounted. The jogging fingers are in the form of rockers whose rear ends are acted upon by tension springs 47. The rear portions of the fingers are forked and provide a narrow stud 48 which is adapted to engage slits in the stationery and correct inaccuracies in the advancement of the stationery strips. The plate is further provided with a rig-

idly connected rearwardly extending arm 49 having a roller 50 which engages the cam 38 and rocks the jogging fingers rearwardly in timed relationship to the rotation of the shaft 35. The fingers are adapted to engage the stationery through slots 51 provided in the top 33 of the frame. The cam 38 is arranged so that the fingers advance just after the mutilated portion of the feed-wheel has been presented towards the stationery and the strips are normally freed from the feed mechanism to enable the fingers to make proper adjustments while advancing the strips.

The presser mechanism C comprises a rock-shaft 52 provided at its right end, as viewed in Fig. 3, with a crank 53 which is connected by a pitman 54 to a rocker member 55 pivotally connected to the frame by a screw 56 and equipped with a roller 57 which engages the cam 49 on the shaft 35. A compression spring 58 urges the crank 53 downwardly. The presser member comprises a bent wire member 59 whose ends encircle the shaft 52 and are pivotally mounted thereon. A coil spring 60 is rigidly connected at 61 to the shaft 52 and has an arm 62 engaging the member 59 so that the latter is yieldingly urged upwardly or downwardly when the shaft is rocked by the mechanism described above. The member 59 is provided with upwardly extending loop portions 64 to prevent the folds in the stationery from accidentally dropping above the member 59.

The guiding mechanism D, is provided to direct the record-strip into a proper refolded condition within the record compartment 12 and comprises a concavo-convex member 65 which is pivoted to the upper portion of the casing at 66 and is provided with an operating arm 67 which is yieldingly connected to a rock member 68 by means of a stiff spring 69. A cam member 70 is mounted on a stub shaft 71 extending outwardly from the frame member 31 and has a gear 72 intermeshing with the gear 73 on the shaft 35. The gear 72 has twice as many teeth as the gear 73 so that it makes one revolution to each two revolutions of the shaft 35. The rock member 68 is pivoted to the frame 31 at 74 and is equipped with a roller 75 which is held in engagement with the cam 70 by means of a tension-spring 76. Thus it will be understood that the member 65 will be swung from the position shown in Fig. 1 to the position shown in Fig. 3 alternately during each rotation of the shaft 35.

The continuous-form stationery strips 16 are provided with lines of weakening which form the junctions between forms and facilitate the zig-zag folding. It has been found that the record strips will refold in the record compartment, with less difficulty, if the folds are in the same directions as they were in the supply compartment. Accordingly, the printed forms, which are numbered consecutively, should be fed into the machine so that the guide mechanism D will be in a proper position, relative to the feed mechanism, to insure refolding in the same direction as in the supply compartment. To accomplish this the forms are printed so that the even numbers always appear in the same relative position in the supply packet. In order that the operator may know whether the feed mechanism is properly positioned to receive either the even or odd numbered tickets, an indicating device is provided, as shown in Figs. 5 and 6. It may comprise a stub shaft 77 adapted to slip into a journal member 78 mounted on a side wall of

the casing, and has a rigidly connected wheel 79 provided with an integral gear 80 intermeshing with a gear 81 which is rigidly connected to the shaft 35. There are twice as many teeth in the gear 80 as in the gear 81, so that the wheel 79 will make one-half a revolution for each full revolution of the shaft 35. The wheel 79 is provided with a suitable legend which will show through an opening in the platen and tell the operator whether even or odd numbered tickets should be in position over the platen. As is shown in Fig. 5, a large gear 82 is rigidly connected to the shaft 35 and serves to drive the presser roll shaft through the medium of the gear 26. The indicating wheel may be held in the journal 78 by having its lateral travel limited by the gear 82.

To load the machine the operator leads stationery strips 16 from the supply compartment around the guide roll 12 and over the platen 21 to a position where slits 16a in the strips are engaged by the jogging fingers 42. As stated above, the handle 36 should be rotated until the indicating wheel 79 shows that the guide mechanism is in proper position to receive the even or odd numbered forms. The door 13 and cover A' may then be closed and the machine is ready for operation in the ordinary manner.

The foregoing description has been given for clearness of understanding only, and no unnecessary limitations should be understood therefrom, but the appended claims should be construed as broadly as permissible in view of the prior art.

I claim:

1. In an autographic register: a casing provided with a platen forming a cover for an underlying supply-compartment, and a closed record-compartment; feed-mechanism at the rear of said platen adapted to feed continuous-form stationery from a zig-zag folded packet in said supply-compartment over said platen to said record-compartment, the forms of said stationery bearing serially alternating indicia to indicate the direction of their original folds in said packet; movable guide-means in said record-compartment adapted to direct said stationery into folds alternately at opposite ends of the record-compartment; a movable loading-indicator exposed at the rear of said platen adjacent to said feed-mechanism bearing alternate indicia relating to that on the stationery forms and adapted to show which form the guide means is then adapted to refold properly, said indicator being observable when the compartments are closed; and means for actuating said guide-means and loading-indicator in timed relation to the feed mechanism so that the visible indicia is changed after each operation of the feed-mechanism which advances one form length of stationery.

2. In an autographic register: a casing having a platen, a supply-compartment for a zig-zag folded packet of stationery strips provided with register perforations, and a record-compartment for receiving a record strip of said stationery; feeding and aligning mechanism including a reciprocating jogging member for advancing said strips less than one-form length during each operation, said jogging member being in its foremost position at the completion of a feeding operation so as to engage register perforations in the strips and facilitate initial loading of the machine; a strip-guiding member pivotally mounted in said record-compartment to direct refolding of said strip into a zig-zag folded pack-

et; a packet-compressing member pivotally mounted in the casing to periodically compress one end of the record packet; and means operable by said feeding mechanism for actuating said strip-guiding member and compressing member in timed relation to the advance of the stationery.

3. In an autographic register having a platen over which continuous-form stationery strips 10 provided with register perforations may be led; feeding and aligning mechanism comprising: upper and lower cooperating feed wheels adapted to advance said strips less than a form-length and release the same; and jogging means mount-

ed in front of said feed wheels to reciprocate in said casing in timed relation to the movement of the feed wheels, and upon release of the strips by the feed wheels to engage perforations and complete the advance to one-form length, bringing the perforations into longitudinal alignment with the bite of said feed wheels.

4. A device specified in claim 3, in which the feed wheels are adapted to reengage the strips at the completion of the forward advance of a set 10 of forms so that the strips are engaged by both of the feed wheels and jogging means when the forms are in inscription receiving position.

LOUIS JENSEN.
